DISPENSER WITH POSITIVE INERTIAL FEED
Fay E. Null, Okaloosa County, Fla.
(Box 158, Shalimar, Fla.)
Filed Mar. 12, 1964, Ser. No. 351,479
11 Claims. (Cl. 222—196.2)

This invention relates to an improvement in dispensers such as salt-cellars that prevents the clogging of the discharge openings when the ambient air is persistently humid. For high relative humidity it is necessary to provide a lid to prevent continued contact of the moist air with the openings to and interior of, dispensers which contain materials such as common salt which absorb moisture from humid air. However, the dispenser discharge openings and the interior are exposed to a new intake of moist air during each shake so that is practically impossible to use a material such as common salt without partial clogging of the portion in proximity to the exhaust openings. For continuous use of a dispenser at high relative humidity of the surrounding air, it is necessary, therefore, to provide both a lid to keep out the moist air except when shaking the dispenser and a positive feed that exhausts a given volume of material at each shake regardless of said material becoming somewhat moist from contact with moist air when the lid is briefly open during each shake. An inertial plunger is the most natural feed device, as its actuation is produced by the usual shaking motion. In the inverted position of the dispenser, spring arms hold the tip of the plunger back from the top of the exhaust cylinder so that the same volume of salt always fills the exhaust cylinder. Then upon deceleration of the dispenser the relatively heavy plunger travels on down and pushes the given load of salt in the exhaust cylinder against the spring closed exhaust lid, causing it to open with discharge of the salt. The plunger and lid are then returned to the normal position by the spring action of said spring arms in readiness for the next shake. The motion of the plunger and attached spring arms also breaks up any residual clumping of the material in said dispenser.

It is, therefore, among the objects of the present invention to provide a spring loaded lid to protect the dispenser exhaust and interior from continuous exposure to moist air.

Another object of the present invention is to provide positive feed of the same volume of material such as salt for each shake of the dispenser.

Another object of the present invention is to use an inertial feed plunger that is normally positioned by spring means to allow material to flow around the plunger tip and to fill an exhaust cylinder, always with a fixed volume of material, so that deceleration of the plunger at the end of a shake stroke will drive said fixed volume of material against the exhaust lid and will open said lid for the exhaust of the material; said spring action then returning said plunger and lid to their normal positions.

Another object of the present invention is to provide positioning springs for the inertial plunger that break up any residual clumping of the material.

Another object of the present invention is to provide a material discharge lid that is at an appreciable angle to the horizontal so that the material discharged by the plunger will readily fall off of said lid and be spread laterally by discharge grooves on the lid surface.

Another object of the present invention is to provide a thin coating over all metal parts exposed to a material such as common salt, by a plastic not affected by continued contact with the material, such as silicone rubber

2

which prevents staining and contamination from salt-metal contact.

Another object of the present invention is to provide a thin, sharp edge on the lower end of the exhaust cylinder so that contact with the closing lid at an oblique angle to said lid surface will displace any grains of material on the line contact between said sharp edge and said lid so that an approximately air tight seal can be made.

10 Objects and advantages other than those set forth will be apparent to those skilled in the art from the following description when used in connection with the accompanying drawings in which:

15 FIG. 1 is a plan view of the dispenser in the inverted, ready-to-shake position.

FIG. 2 is a cross-sectional view along line 2—2 in FIG. 1. It shows the inertial plunger held in its pre-shake position by attached spring arms and with material filling the discharge cylinder and resting against the closed lid.

20 FIG. 3 is a bottom view of the dispenser of FIGS. 1 and 2.

FIG. 4 is a plan view of the inverted dispenser at the end of a shake stroke.

25 FIG. 5 is a cross-sectional view along line 5—5 in FIG. 4. It shows the dispenser walls stopped at the end of a shake stroke, with the inertial plunger traveling on down to open the lid and push out the material that was in the exhaust cylinder.

30 FIG. 6 is a bottom view of the dispenser of FIGS. 4 and 5.

FIG. 7 is an enlarged, fragmentary side view of the lid and discharge cylinder in the direction 7 of FIG. 5.

35 Referring more particularly to the drawings by characters of reference, reference numeral 1 shows the walls of the dispenser with the base plate 2, and the cork 3 inserted in the filling hole 4. The plunger 5 is positioned by flexible spring arms 6 whose ball ends 7 slide up and down along the edges 8, 9, 10, and 11. In 40 this preshake position, FIGS. 1, 2, and 3, the rod end 12 of plunger 5 is held above the top end of exhaust cylinder 13, allowing salt 14 to slide down sloping side walls 15 to fill exhaust cylinder 13, with an approximately constant volume of material. FIGS. 2 and 3 show the pre-shake condition for the said exhaust cylinder 13 as closed by lid 16 which is hinged at 17 and normally held in the closed position by spring 18.

45 FIG. 5 shows the walls 1 stopped at the end of a shake stroke, with the plunger 5, because of its inertia, traveling on down with the rod end 12 forcing lid 16 open and driving out the material stored in the discharge cylinder 13 in the preshake condition of FIG. 2. The bottom spring arms 6 are bent by the downward stroke of plunger 5 ready to return it to the position of FIG. 2. The up-and-down motion of plunger 5 and its spring arms 6 keep the material 14 from lumping, the lumping tendency being due to the small amount of moist air that may enter discharge cylinder 13 during the time lid 16 is open after the material is discharged from said cylinder 13. A thin film 19 resistant to continued contact with the given material, such as silicon rubber for common salt, is applied to all metal surfaces that come into contact with the material. FIG. 7 indicates how the salt 14 discharged from the exhaust cylinder 13 by rod 12 falls on the inclined lid 16 and is scattered laterally by grooves 20. As rod 12 and plunger 15 are forced by bottom springs 6 upward into their normal position, the lid 16 is forced by spring 18 against the knife edge end 21 of said discharge cylinder 13, the top surface of said lid 16 being at an oblique angle to the inner wall of said discharge cylinder 13,

so that any grains of material hanging to the inclined surface of lid 16 or the knife-edge 21 are pushed aside allowing a good seal between said edge 21 and said lid 16.

It is claimed and desired to secure by Letters Patent:

1. In a dispenser with positive inertial feed, the combination of a container, a discharge lid connected to said container by spring-type distortion means such that said lid remains closed by said spring-type distortion means in the preshake, inverted position of said dispenser, a discharge chamber in said container whose lower end is closed by said lid that contains the approximate volume of material to be discharged in a downward stroke, and an inertial plunger within said container having spring-type distortion means for positioning said plunger in the preshake condition so that its lower end is just above and of approximately the same diameter as said discharge chamber so that in a shake stroke the lower end of said plunger drives the material in said discharge chamber down past said discharge lid.

2. In a dispenser with positive inertial feed, the combination of a container, a discharge lid connected to said container by spring-type distortion means such that said lid remains closed by said spring-type distortion means in the preshake, inverted position of said dispenser, a discharge chamber in said container whose lower end is closed by said lid and that contains the approximate volume of material to be discharged in a downward shake, and an inertial plunger within said container having flexible spring arm means for positioning said plunger in the preshake position so that its lower end is just above and approximately the same diameter as said discharge chamber so that in a shake stroke the lower end of said plunger drives the material in said discharge chamber down past said discharge lid, and said spring arm means for positioning said plunger in the preshake condition is symmetrically arranged around said plunger so as to guide it in the shake down stroke and return up stroke, and said spring arms are of such length and such angle of attachment to the axis of said plunger that displacement either up or down from the normal preshake position distorts said spring arms so that they provide a restoring force toward the normal, preshake position.

3. In a dispenser with positive inertial feed, the combination of a container, a discharge lid connected to said container by spring-type distortion means such that said lid remains closed by said spring-type distortion means until acted upon by the inertial force of a plunger within said container near the end of a shake, downward stroke, second spring-type distortion means and an inertial plunger that in the preshake condition is positioned by said second spring-type distortion means to allow the material to be dispensed to flow past its lower end to said closed lid.

4. In a dispenser with positive inertial feed, the combination of a container, a discharge lid connected to said container by spring-type distortion means such that said lid remains closed by said spring-type distortion means until acted upon by the inertial force of a plunger within said container near the end of a shake down stroke, second spring-type distortion means and an inertial plunger that in the preshake condition is positioned by said second spring-type distortion means to allow the material to be dispensed to flow past the lower end to said discharge lid, said discharge lid being inclined at an angle to the horizontal to prevent the retention of discharged grains of material on its surface, and a sharp edge on the discharge opening of said dispenser such that an extension of the inner surface of said sharp edge makes an oblique angle to the surface of said discharge lid, so that as said lid closes any grains of clinging material may be pushed aside permitting a good seal between said knife edge and said lid.

5. In a dispenser with positive inertial feed, the combination of a container, a discharge lid connected to said

container by spring-type distortion means such that said lid remains closed by said spring-type distortion means in the preshake, inverted position of said dispenser, until acted upon by the inertial force of a plunger within said container near the end of a shake downward stroke, second spring-type distortion means and an inertial plunger that in the preshake condition is positioned by said second spring-type distortion means to allow the material to be dispensed to flow past the lower end to said discharge lid, said discharge lid consisting of a hinged plate, a flexible spring member to force said lid against the discharge opening of said dispenser, grooves on said lid to scatter the discharged material, a sharp edge on the discharge opening of said dispenser, and an oblique angle between the extension of the inner wall of said sharp edge and the surface of said lid for displacement of any clinging grains of material that might otherwise prevent a good seal between said lid and said dispenser.

6. In a dispenser with positive inertial feed, the combination of a container, a discharge lid connected to said container by spring-type distortion means such that said lid remains closed by said spring-type distortion means until acted upon by the inertial force of a plunger within said container near the end of a shake downward stroke, second spring-type distortion means and an inertial plunger that in the preshake condition is positioned by said second spring-type distortion means to allow the material to be dispensed to flow past the lower end to said discharge lid, said discharge lid consisting of a hinged plate, a flexible, curved spring member to force said lid against the discharge opening of said dispenser, grooves on said lid to scatter the discharged material, a sharp edge on the discharge opening of said dispenser, and an oblique angle between an extension of the inner wall of said sharp edge and the surface of said lid for the displacement of any clinging grains of material that might otherwise prevent a good seal between said lid and said dispenser, said second spring-type distortion means consisting of spring arms symmetrically attached to said plunger so that they guide said plunger in its up and down motion, and said spring arms having vertical force components when bent by displacement from the preshake position such that a displacement of said plunger down or up causes distortions of said spring arms that produce restoring forces toward said normal, preshake position.

7. In a dispenser with positive inertial feed, the combination of a container, a discharge lid connected to said container by spring-type distortion means such that said lid remains closed by said spring-type distortion means in the preshake, inverted position of said dispenser, a discharge chamber in said container whose lower end is closed by said lid that contains approximately the desired volume of material to be discharged in a downward shake stroke, and an inertial plunger within said container having flexible spring rods attached at both ends, said rods having ends that slide up and down on the walls of said dispenser, said flexible spring rods being of such length and at such angles to the wall surface that they are relatively little distorted in the desired preshake position of said plunger, but such that displacement either up or down from this preshake position of said plunger causes a bending of said rods that exerts a restoring force toward said preshake position.

8. In a dispenser with positive inertial feed, the combination of a container, a discharge lid connected to said container by spring-type distortion means such that said lid remains closed by said spring-type distortion means in the preshake, inertial position of said dispenser, and an inertial plunger within said container having flexible spring rods attached at both ends, said rods having ends that slide up and down on the walls of said container to keep said plunger in a central position in said container, said flexible spring rods having such lengths and angles to the wall surfaces that they are relatively little distorted in the desired preshake position of said plunger, but such that

displacement either up or down from this preshake position causes a bending of said rods that exerts a restoring force toward said preshake position.

9. In a dispenser with positive inertial feed, the combination of a container, a small discharge opening in said container, and an inertial plunger within said container whose lower end is slightly above said discharge opening when said dispenser is in the preshake position, and flexible spring rods attached to both ends of said plunger, said rods having ends that slide up and down on the walls of said container as guides to keep said plunger in a central position in said container, said flexible spring rods having such lengths and angles to the walls that they are relatively little distorted in the desired preshake position of said plunger, but such that displacement either up or down from this preshake position causes a bending of said rods, that exerts a restoring force toward said preshake position.

10. In a dispenser with positive inertial feed, the combination of a container, a discharge lid connected to said container by spring-type distortion means such that said lid remains closed by said spring-type distortion means in the preshake inverted position of said dispenser, and an inertial plunger within said container having spring-type, flexible distortion means to position said plunger with its lower end slightly above such discharge lid when said dispenser is in its inverted, preshake position so that at the end of a shake down stroke some material in the vicinity of said lid and the end of said plunger, will be discharged past said lid, and a thin, protective coating on said metal, flexible, spring-type distortion means for positioning said

plunger that will give permanent protection against contact with the material to be dispensed.

11. In a dispenser with positive inertial feed, the combination of a container, a discharge lid connected to said container by spring-type distortion means such that said lid remains closed by said spring-type distortion means in the preshake, inverted position of said dispenser, and a discharge chamber in said container whose lower end is closed by said lid and whose upper, open end is somewhat below the lower end of an inertial plunger within said container in the prestroke position, so that the material to be dispensed can flow past the bottom end of said plunger to fill said discharge chamber, with a constant volume of material in readiness for discharge past said lid due to the downward motion of said plunger at the end of a shake-stroke, and an inertial plunger positioned in said container in the prestroke condition with its lower end somewhat above the top of said discharge chamber by metal, spring-type distortion means, and a thin film coating for said metal, spring-type, distortion means for positioning said plunger that will give permanent protection against contact with the material to be dispensed, and will not peel from the flexible surfaces of said metal, spring-type, distortion means.
